UNITED STATES PATENT OFFICE.

IRA J. HOLLENSBE AND EARL F. SHELLEY, OF GREENSBURG, INDIANA.

BROOM-ASSEMBLING MACHINE.

Application filed January 26, 1924. Serial No. 638,766.

To all whom it may concern:

Be it known that we, IRA J. HOLLENSBE and EARL F. SHELLEY, citizens of the United States, residing at Greensburg, in the county 5 of Decatur and State of Indiana, have invented certain new and useful Improvements in Broom-Assembling Machines, of which the following is a specification.

This invention relates to improvements in 10 machines for assembling broom material.

An object of the invention is to provide a 15 machine for assembling broom material of different grades, with a coarse grade of material forming a filler, a finer grade of material forming a cover for the filler, and a still finer grade of material forming a 20 hurl or outer covering of the broom, adapted to position the layers relative to one another so that in the compressing operation, the covers and hurl will be evenly distributed over the filler. In carrying out this 25 object it is designed to overcome disadvantages at present experienced in the manufacture of brooms which occur from arranging the filler, the covers, and the hurl in concentric relation which when compressed to form the finished broom is disarranged to such an extent that in some instances the filler is exposed at the sides of 30 the broom. In overcoming this disadvantage the covers and the hurl are placed on the filler so that at diametrically opposite points the sections of the covers and the hurl are substantially greater than at the intermediate points, the thickened portions of 35 the hurl being arranged in intermediate relation with respect to the thickened portions of the covers so that the broom bundle will be round, this arrangement of the layers of material providing an evenly distributed 40 layer of covers and hurl over the filler in the finished broom.

Another object of the invention resides in 45 providing a broom assembling machine with means for grading the material and holding the layers of the graded material in the relation above mentioned while the same is being inserted through a guiding sleeve which is adapted to compress the bundle and apply a binding ring thereto, so that the bundle may be subsequently removed from this machine and conveyed to a compressor.

A further object of the invention resides in providing a simple and efficient construction for mounting the binding ring and guiding the broom material through said ring as well as determining the position of the ring on the broom bundle, means being provided for permitting the ready removal 55 of the bundle from the guiding and ring holding means.

The invention further comprehends other objects and improvements in the details of construction and arrangement of parts 60 which are specifically pointed out in the following description and claims describing a preferred form of the invention, it being understood that variations may be made in the construction and operation of the machine without departing from the spirit and scope of the invention as described and claimed.

In the drawings, forming a part of this 65 application,

Figure 1 is a side elevation of the broom assembling machine with a bundle of material in assembled relation.

Figure 2 is an elevational view taken at 70 right angles to Figure 1.

Figure 3 is a side elevation of the machine showing the hinged section of the guiding sleeve moved to open position and parts of the assembling and grading unit removed to show the structure and relation thereof 75 to the guiding sleeve.

Figure 4 is a vertical sectional view 80 through the machine showing the parts in position for receiving a charge of material to be assembled.

Figure 5 is a plan view of the base member showing the method of supporting the binding ring therein.

Figure 6 is a horizontal sectional view 85 taken on the line 6—6 of Figure 1.

Figure 7 is a transverse section through a bundle of assembled broom material on the line 5—5 of Figure 1, showing the binding ring holding the material in assembled relation.

1 indicates a bench or other desirable supporting structure for the assembling machine on which is mounted the base plate 2, having a U-shaped base member 3 mounted on one end thereof at the upper end of 90 which are secured a U-shaped ring and sup-

porting plate 4, and a ring positioning plate 5 in superposed relation thereon adapted to support in position the binding ring 6, in a proper position with respect to the remaining structure for receiving a charge or bundle of broom material.

The guiding sleeve 7 for guiding the broom material through the ring 6 is mounted on the ring positioning plate 5 and formed of a pair of sections 8 and 9, the section 8 forming a stationary section, which is secured to the base member 3 thru securing screws or the like 10 which also extend through the ring supporting and positioning plates for securing said parts in assembled relation with the base. The section 9 of the guiding sleeve is hinged to the stationary section 8 and positioned on the base member so that it may overlie the open end thereof, so that it may be swung to open position to permit removal of the bundle held by the ring from the sleeve and base member. The central portion of the hinged section 9 is provided with a depending portion 11 adapted to engage the ring member 6 to force the same in position against the positioning member 5 so that the binding ring will be positioned relative to the guiding sleeve 7 so that a bundle of material fed through said guiding sleeve will be directed through the ring. This guiding sleeve 7 is of frusto-conical form, the lower diameter of which is equal to the inner diameter of the ring 6, in order that all material fed through said sleeve will be directed through the binding ring. A latch is provided at 12 on the free end of the hinged section 9 of the guiding sleeve for cooperation with the radial flange 13 on the stationary sleeve section 8 for holding said section in assembled sleeve forming relation.

A stationary hollow sleeve member 14 is mounted on the end of the base opposite to the base member 3 and receives an interfitting rotatable sleeve 14' provided with a laterally extending arm 15 carrying a broom material assembly and grading unit 16 at the end thereof adapted for cooperation with the guiding sleeve 7. This assembling and grading unit provides an outer frusto-conical sleeve member 18 formed of a pair of assembled half sections provided with flanges 19 secured to the laterally extending arm 15 as indicated at 20, the meeting edges of the 55 section of the member 18 being curved upwardly at the upper edges as indicated at 21 for determining the position of the central or intermediate sleeve member 22 which is also formed of a pair of half sections having the edges extended outwardly and secured between the flanges of the half section of the outer member 18 as clearly shown in Figure 6, the lower end of this intermediate sleeve member terminating in a horizontal plane and in spaced relation with re-

spect to the outer sleeve member 18. From Figure 6, it will be noted that the intermediate sleeve member 22 is of substantially elliptical form in cross section, in order to provide pockets 23 and 24 substantially crescent shaped for receiving the covers and hurl to form the outside or finishing layers for the broom, the covers being indicated in Figure 7, at 25, and the hurl at 26. An inner sleeve 27 of frusto-conical form is mounted within the sleeve 22 and in concentric relation with the sleeve 18, the bottom end of which terminates in the same horizontal plane, and in spaced relation with the bottom end of the outer and intermediate sleeve, and the upper end of which extends above the upper end of the intermediate sleeve as clearly shown in Figures 3 and 4, the central portion of this inner sleeve being adapted to receive the filler indicated at 28 in Figure 7. This inner sleeve 27 is also formed of a pair of half sections secured in assembled relation by channel members 29 secured to opposite sides of the intermediate sleeve member 22 for supporting said inner sleeve in spaced relation therewith. This sleeve 27 cooperates with the intermediate sleeve in forming the pocket 24, for the reception of the cover and the upper edge of each of the sleeve members 95 forming the brush assembly and grading mechanism is provided with an outwardly flared portion 30 so that the material being fed into the sleeve members will slide in easily and not be scraped or shaved by the 100 upper edges of these members.

With the parts positioned as shown in Figures 1, 2, and 4, the hurl and the covers are fed into the machine through the upper ends of the sleeve members 22 and 18, and are guided by the sleeve members 8 and through the ring 6 until the ends rest on the base plate within the base member 3, the sleeves 18 and 22 grading the material from the outer toward the inner portion thereof and positioning the hurl and covers in crescent shaped section, the thicker portions of which occur at diametrically opposite points in each section, the section being arranged in alternate relation, after which the filler material is fed through the inner sleeve 27 and pushed through this sleeve until the lower ends engage the base plate 2. This assembles a bundle with the filler or coarse material in the central portion and two layers of finishing material distributed around the filler, the whole being bound by the ring 6 as the guiding sleeve 8 directs all of the material through this ring. The hinged section 9 may now be swung to the open position as shown in Figure 3, by releasing the latch 12 from the flange 13 and will permit the rotation of the support 14 to carry the assembling mechanism 16 and the broom bundle outwardly from the guiding member 130

and the U-shaped base member for subsequent removal from the unit to be conveyed to a compressing machine.

It has been found very difficult in practice to arrange the covers and the hurl over the fillers in such a manner in assembling the bundle that they will be equally distributed over the filler after the same has been compressed, as the compression operation 5 arranges the relationship of the layers of covers and the hurl so that at some places the filler is exposed. It has been found, however, that by forming the covers and hurl as indicated in Figure 7, these sections will be 10 evenly distributed or substantially so over the filler during the compressing operation, so that in the finished broom, the covers and hurl will prevent exposure of the filler thru the sides of the broom.

20 It will be apparent from the above description that the invention includes a simple and effective structure and association of parts for assembling the various layers of the broom bundle for binding them in a ring 25 preparatory to being conveyed to a compressing machine and also that a particular relation has been provided between these several grades of material used in forming a broom, so that the coarse material will be in 30 the central portion and be protected and covered by finer grades of material which is positioned over the outer surface of the filler.

It is also to be understood that any kind 35 of material adapted for use in broom making for supplying the various grades of material used in making the filler, the covers, and the hurl may be used in connection with this machine, including such material as bamboo, 40 rattan, bass, basine, hickory splits, Spanish rush, broom corn, etc., separately or in combination with each other.

What is claimed is:

1. A broom assembling machine including 45 a base plate, means for removably supporting a binding ring above said base plate in spaced relation thereto, guiding means associated with the ring supporting means for guiding broom material through said ring to form a bundle, and a material assembling and grading unit movably mounted on said base plate comprising a plurality of assembling members arranged in spaced relation within one another, for grading and assembling broom material.

2. A broom assembling machine including 50 a base plate, means for removably supporting a binding ring above said base plate in spaced relation thereto, guiding means associated with the ring supporting means for guiding broom material through said ring to form a bundle, and a material assembling and grading unit movably mounted on said base plate above said ring supporting means 55 having a plurality of frusto-conical sleeve

members arranged in interfitting spaced relation within one another, the inner and outer members being circular in cross section and concentric, and the intermediate member being of oval shape in cross section and arranged intermediate the inner and outer members in spaced relation thereto.

3. A broom assembling machine comprising a base plate, a binding ring adapted for mounting above the base plate, guiding means for guiding broom material into said ring, and a material assembling and grading unit movably mounted on the base plate having a plurality of interfitting relatively 70 spaced frusto conical sleeve members including an outer sleeve member formed of assembled half sections having radially extended flanges thereon, an intermediate sleeve member formed of assembled half sections having diametrically opposite radially extending flanges secured between the corresponding flanges of the outer member for assembling the intermediate and the outer members in spaced relation, and an inner member formed of half sections having diametrically opposite outwardly directed flanges at the juncture of the sections attached to the intermediate portion of the sections of the intermediate member, whereby said sleeve members are mounted in 80 spaced relation relative to one another for receiving, assembling, and grading material to be secured in a bundle by said ring.

4. A broom assembling machine including 85 a U-shaped base member, a binding ring removably mounted in the upper end portion of said base member, a guiding sleeve having a hinged section mounted on the upper end of said base member for guiding broom material through the ring, and a broom material assembling and grading unit having a 90 plurality of spaced interfitting frusto-conical members for receiving, assembling, and holding material in graded relation while being fed through the guiding sleeve and ring.

5. A broom assembling machine including 95 a base member, a binding ring removably mounted in the upper portion of said ring member, a guiding sleeve having a hinged section mounted on the upper end of said base member for guiding broom forming material through the ring, and a broom material assembly and grading unit movably mounted over said guiding sleeve adapted 105 for receiving, assembling, and holding materials in graded relation while being fed through the guiding sleeve and ring to form a bundle and adapted in its movement relative to said guiding sleeve to remove the 115 bundle and ring binding the same from the sleeve and the base member.

6. A broom assembling machine including 120 an open ended base member, a binding ring removably mounted in the upper por- 125

tion of said base member, a guiding sleeve having a hinged section mounted on the upper end of said base member for guiding the broom forming material through the ring, 5 said hinged section having a depending lug formed thereon for positioning the binding ring in a predetermined relation thereto in the base member, and a broom material assembling and grading unit movably mounted 10 relative to said guiding sleeve for receiving, assembling, and holding material in graded relation, while being threaded thru the guiding sleeve and ring to form a bundle, said unit being movable for removing the 15 finished bundle from said guiding sleeve and base member.

7. A broom assembling machine including a base plate, a U-shaped base member mounted on said base plate, a binding ring supporting and positioning means mounted on the upper end of said base member adapted to removably receive and position the binding ring therein, a guiding sleeve mounted on the upper end of said base member and 20 positioning means having a hinged section provided with a depending binding ring holding lug adapted in closed position to cooperate with said positioning means to hold the binding ring in a predetermined 25 relation with said guiding sleeve, said guiding sleeve having a diameter at the lower end thereof equal to the inner diameter of the binding ring, and a broom material assembly and grading unit movably mounted 30 above said guiding sleeve and adapted for cooperation therewith for guiding and grading broom material to be compressed by said guiding means and inserted through said binding ring to form a bundle, said hinged 35 section being adapted to open to permit the movement of the assembling unit and the 40

assembled bundle from the guiding sleeve and base member.

8. Assembling means for broom material comprising a binding ring, and means for 45 assembling different grades of broom material in a bundle in said ring, in predetermined relation, comprising means adapted to receive and hold filler material in the central portion of the bundle, means adapted to receive and hold cover material around said filler material outwardly thereof, said last mentioned means being spaced a greater distance at a pair of opposite 50 points from said filler holding means than at a pair of intermediate points, and additional means adapted to receive and hold a burl outwardly of the cover material, said additional means being spaced a greater distance from said cover holding means at 55 a pair of opposite points intermediate the points of greater diameter of the cover holding means, than at the point of greater diameter of the cover holding means.

9. Means for assembling broom material 60 in a binding ring, in predetermined relation, including a member formed with a central passage for receiving filler material, a second mentioned member outwardly of the 65 first mentioned member forming a passage 70 around the first member for cover material, and another member, around the last mentioned member forming a passage for burl, said two last mentioned members being formed to provide passages having portions 75 of greater width at diametrically opposite points arranged in alternate relation.

In testimony whereof we affix our signatures.

IRA J. HOLLENSBE,
EARL F. SHELLEY.
